UNITED STATES PATENT OFFICE.

WILLIAM KOPP, OF DETROIT, MICHIGAN.

WINDOW-RAISING DEVICE.

1,260,550.

Specification of Letters Patent. Patented Mar. 26, 1918.

Application filed April 23, 1917. Serial No. 163,844.

To all whom it may concern:

Be it known that I, WILLIAM KOPP, a citizen of Russia, residing at Detroit, in the county of Wayne and State of Michigan, have invented certain new and useful Improvements in Window-Raising Devices, of which the following is a specification, reference being had therein to the accompanying drawings.

10 This invention relates to a mechanically operated window and has special reference to a device that may be advantageously used for raising and lowering a sash relative to a frame, particularly those sashes housed 15 within the side walls or panels of an automobile body or door and adapted to be raised relative thereto to close the side of an automobile body or provide a panel or window on the upper edge of an automobile 20 door.

The primary object of my invention is to provide simple and effective means that may be easily and quickly installed in the wall of an automobile body or a door body to safely 25 raise and lower the window sash, the sash being automatically swung into and out of engagement with the window frame without any danger of the sash becoming accidentally displaced.

30 Another object of my invention is to provide a sash raising and lowering device that may be bodily installed and bodily removed from the wall or door of an automobile body, and this is accomplished without dis- 35 turbing or removing any part of the automobile body or door.

A still further object of my invention is to provide a window sash raising and lowering mechanism wherein the parts are constructed with a view of reducing the cost of manufacture and at the same time retain those features by which safety, durability, ease of operation, and applicability to various types of motor vehicles are secured. 45 With such ends in view, my invention resides in the novel construction, combination and arrangement of parts to be hereinafter specifically described and then claimed.

Reference will now be had to the drawings, wherein—

Figure 1 is a vertical sectional view of a portion of an automobile door provided with the sash operating mechanism;

Fig. 2 is a side elevation of the sash operating mechanism, partly broken away; 55

Fig. 3 is an enlarged detail sectional view of a portion of the mechanism;

Fig. 4 is a front elevation of a detached locking member;

Fig. 5 is a cross sectional view of the same; 60

Fig. 6 is a side elevation of a detached pressure member;

Fig. 7 is an edge view of the same;

Figs. 8 and 9 are detail views of a link of a chain forming part of the operating mechanism;

Fig. 10 is a front elevation of a sash link, and

Fig. 11 is a plan of the same.

Considering the main views of the drawing, there is shown in Fig. 1 a portion of a door frame having an inner wall 1 and an outer wall 2 affording a space or pocket 3 for a sash, glass plate or panel 4. The sash is adapted to be completely housed within the pocket 3 and the lower rail of said sash has a hook member 5 adapted to engage a bracket 6, carried by the upper inner edge of the outer wall 2, so that the sash 4 may be supported in a raised or elevated position 60 out of the pocket 3.

The mechanism employed for raising and lowering the sash 4 comprises a hanger plate 7 disposed in parallelism with the inner side of the wall 1 and supported relative thereto 65 by a flange 8 at the upper edge of the hanger plate secured on the upper edge of the inner wall 1. The hanger plate has a large central opening with the marginal edges of the opening reamed or outturned to 70 provide an annular ball race 9, and at the same time this ball race is formed, teeth 10 are provided circumferentially of the ball race and on the inner wall thereof, as best shown in Fig. 3, said teeth constituting a 75 stationary clutch member.

In the ball race member 9 are balls or anti-frictional members 11 and on said balls is an outer rotatable ball race member 12 having flanges 13 connected by screws 14 or 100 other fastening means to pin wheel 15, said wheel having equally spaced pins or studs 16 contiguous to the periphery thereof.

The outer ball race member 12 has a central opening 17 alining with an opening 18 105 in the inner wall 1 of the door frame. Ex.

tending through the opening 18 and fitted in the opening 17 is an operating shaft 19. On the outer end of the shaft 19 is a semi-spherical ball member 20 engaged by a 5 socket member or face plate 21 suitably secured to the wall 1. A handle or crank 22 on the end of the shaft 19 permits of this shaft being easily rotated and said handle or crank is formed with a shield 23 to exclude 10 dirt and other foreign matter that might interfere with the movement of the ball member 20 in the socket member 21.

On the operating shaft 19 adjacent the outer ball race member 9, is a presser member 24 having sockets 25 for balls or detents 26. These balls or detents 26 are adapted to extend into recesses 27 in a circular locking member 28 having a beveled toothed periphery 29 adapted to engage the teeth 10 15 of the hanger plate 7 and prevent accidental rotation of the pin wheel 15. The locking member 28 is formed with cupped portions 30 containing guide pins 31 and coiled compression springs 32, said springs maintaining 20 the locking member 28 normally in engagement with the hanger plate 7, and through the medium of the detents or balls 26 holding the pin wheel against accidental rotation. Rotation of the operating shaft 25 30 cause the detents or balls 26 to ride out of the recesses 27 of the locking member 28 thereby pressing the locking member toward the wall 1 and out of engagement with the hanger plate 7, thus permitting of the pin 35 wheel 15 being freely revolved. It is therefore apparent that the presser member 24, detents 26 and locking member 28 constitute means for holding the pin wheel against accidental rotation.

Attached to the pin wheel 15 and adapted to be trained about the pin or stud 16 thereof is a chain composed of links 33, 34, 35 and 36. The link 33 is pivotally connected to the pin wheel 15, as at 37, and all of said links 40 are articulated by connections corresponding to rule joints, so that the joined links can only break in one direction, that of being trained about the pins or studs 16 of the wheel 15. Contiguous to the joints of the 45 links of the chain are notches or recesses 38 to receive the pins or studs 16, and a curved guard 39, carried by the hanger plate 7, will coöperate with the pins 16 in preventing the links thereon from becoming accidentally 50 displaced. The link 35 has a rule joint connection with the link 36 employed for supporting the sash 4, and this particular link has a longitudinal slot 40 to receive a pin or stud 41 of the sash 4. The sash link 36 is 55 normally held at a right angle to the link 35 and said link has a cam portion 42 adapted to engage the outer ball race member 12, when the sash is raised, so that said sash will be forced outward and the hook member 5

placed over the bracket 6 of the outer wall 65 2. To prevent a sudden descent of the sash 4 and cushion a lowering movement of the same, a spiral spring 43 is arranged between the outer ball race member 12 and the locking member 28. The inner convolution of 70 the spring 43 is connected to the locking member 28, and the outer convolution thereof is connected to the outer ball race member 12 of the pin wheel 15, said spring being placed under tension as the sash 4 descends 75 in the pocket 3.

From the foregoing, it will be noted that by removing the operating shaft 19 and the screws or fastening means holding the flange 8 of the hanger plate 7, that the mechanism 80 within the pocket 3 may be bodily removed from the upper end of the pocket, and this is accomplished without disturbing the side walls 1 and 2 of the door frame.

It is thought that the operation and utility 85 of the sash operating mechanism will be apparent without further description, and while in the drawings there is illustrated a preferred embodiment of my invention, it is to be understood that the structural elements 90 are susceptible to such variations and modifications as fall within the scope of the appended claims.

What I claim is:—

1. Means adapted for raising and lowering 95 a sash, comprising a hanger plate having an opening with the walls of the opening toothed, a revoluble pin wheel carried by said hanger plate, a circular locking member having peripheral teeth held normally in engagement with the teeth of said hanger plate and adapted to be shifted out of engagement therewith by rotative movement of said pin wheel to release said pin wheel, a detachable operating shaft for said 100 pin wheel, a link chain having rule joints between the links thereof and one of said links connected to said pin wheel with the other links disposed to be trained on said pin wheel, and a sash carrying link forming 110 part of said chain and normally disposed at right angles to one end of said chain.

2. The combination with a frame having a sash pocket, and a sash in the pocket adapted to be raised and lowered, of sash 115 operating means in the frame pocket and bodily removable from the upper end of the pocket, said means including a hanger plate having an opening surrounded by a ball race and the inner wall of the ball race provided with teeth, a revoluble pin wheel having a ball race, anti-frictional bearings in the ball races of said pin wheel and said hanger plate, a detachable operating shaft for said pin wheel extending through a wall of said 120 frame pocket, a circular locking member interposed between the frame wall of said pocket and said pin wheel and having pe-

ripheral teeth adapted for enguging the teeth of the ball race of said hanger plate for holding said pin wheel against accidental rotation, means actuated by the turning of 5 said shaft to shift said locking member out of engagement with said hanger plate, a chain having one end thereof attached to said pin wheel and adapted to be trained thereabout, and means carried by the other end of said chain adapted for supporting a 10 sash.

In testimony whereof I affix my signature in the presence of two witnesses.

WILLIAM KOPP.
